UNITED STATES PATENT OFFICE.

WILLIS LERICHE, OF ALLENTOWN, PENNSYLVANIA, ASSIGNOR TO CEMENT GUN CONTRACTING COMPANY, OF ALLENTOWN, PENNSYLVANIA, A CORPORATION OF DELAWARE.

MEANS FOR AND METHOD OF ATTACHING SHOOTING STRIPS.

Application filed September 2, 1926. Serial No. 133,176.

This invention relates to means for and a method of attaching shooting strips to secure square edges at the tops of beams.

In the construction of floors and the like there may be formed a floor proper of reinforced concrete supported on the tops of I beams or girders. For reasons such as to protect the supporting members against deterioration at their surfaces, it is very desirable to apply to each of such supporting members a covering of material, such as concrete or cement which may be suitably reinforced. The present invention is particularly applicable in connection with the formation of coverings of material composed of sand and cement and obtained by placing the mixture under high pneumatic pressure in a suitable device and blowing or shooting the mixture from a nozzle of said device against a member at the position where it is desired to apply the material. It should be understood that before leaving the nozzle, the material in the mixture is moistened sufficiently to cause it to stick to the surface to be coated.

An object of the invention is to provide novel means for shaping the covering of a support for a floor or the like.

Another object is to provide a novel method for shaping the covering of a support for a floor or the like.

A further object of the invention is to provide a new method of attaching shooting strips to the lower side of floors or the like.

In carrying out the invention as applied to the covering of an I beam or flanged member on the top of which rests concrete floor, a suitable strip is attached to the lower surface of the floor by suitable adhesive material and in a position parallel to the edge of an upper flange of the supporting member. Then, when the material is shot into place, the covering of the flange will have a square edge. The shaping of the edge of the covering of the opposite upper flange may be effected by using the same or a similar strip in the same manner.

The adhesive material used may be glue, plaster of Paris, gypsum or any suitable quick setting or positively adhering material.

Other objects and advantages will appear upon consideration of the following detailed description and the drawings in which:

Fig. 1 is a sectional view illustrating the

application of a shooting strip at one side 55 of the supporting member or beam;

Fig. 2 is a side view showing a shooting strip attached to the lower surface of the floor; and

Fig. 3 is a cross section view illustrating 60 the use of a tack or nail in holding the adhesive material on the shooting strip.

In Figure 1 there is shown an I-beam 1 on the upper edge of which rests a floor 2 which may be of poured concrete. In practice it is found desirable to cover such beams as 1 with coverings of cementitious material, preferably shot into place. A mixture of cement and sand in proper proportions is placed in a device from which it is forced 70 through a nozzle under suitable pneumatic pressure and driven or shot into place. Before placing from the nozzle of said device the material is sprayed with water to a sufficient extent to make it adhere to the surface 75 against which it is blown. In forming such coverings 3 as shown in Figure 1, difficulty is found in giving the proper shape to the material covering the upper flanges 4 and the lower flanges 5, and particularly the 80 upper flanges, due to the inconvenience of holding suitable shooting strips in position. It is also of great importance to have the shooting strips as simple in form as possible and to have them fastened in position by as 85 simple a means as possible.

According to the present invention use is made of an ordinary strip 6 secured in position by material secured thereto and adhering to the lower surface of the floor 2. For 90 attaching the strip in this way, use may be made of any suitable material such as glue, plaster of Paris, and gypsum. To give satisfactory results the attaching material must be quickly set and must adhere strongly. 95

As shown more clearly in Figure 2, the attaching material may be applied in portions 7 at spaced intervals along strip 6 and such portions of attaching material 7 may be held more strongly in position on the strip 6 by 100 suitable fastening devices such as nails or tacks 8 having their heads projecting slightly above the upper surface of the strip so as to be engaged strongly by the attaching material and held in position on the strip 6. 105

It will be seen that the tacks or nails 8 serve also to space the strip 6 from the lower surface of the floor and that by spacing the

portions of connecting material 7 that spaces are left between the strip and the lower surface of the floor so that the strips can be more easily removed after the covering for 5 the upper flange has been completed.

Although the present invention is illustrated only in connection with the support of the shooting strip against the lower surface of a floor it should be understood that 10 the invention may be applied in the attachment of shooting strips in other positions.

It should be understood that various changes may be made in the shape of the strip and in the means for securing the strip 15 in position and also that various changes may be made in the herein disclosed method of securing proper form for the cementitious covering of the flanges, without departing from the true spirit and scope of the invention. 20

Having thus described my invention, I claim:

1. Means for shaping cementitious material around the flanges at the upper edge of 25 a beam in contact with the lower surface of a floor, comprising a shooting strip adjacent the edge of one of the flanges at the upper edge of said beam, and strip supporting means attached to said strip and adhering to 30 the lower surface of the floor.

2. Means for shaping cementitious material around a flange at the upper edge of a beam in contact with a flat surface of an overhanging member, comprising a strip, 35 and means for supporting said strip in effective position parallel to the edge of one of the flanges at the upper edge of said beam, comprising material attached to said strip at intervals therealong and adhering to the 40 lower surface of said overhanging member.

3. Means for shaping cementitious material placed around the flanges at the upper edge of a beam in contact with the lower surface of a floor, comprising a strip adjacent 45 the edge of one of the flanges at the upper

edge of said beam, and strip supporting means including material adhering to the lower face of said floor and fastening devices extending from said material into said strip. 50

4. A method of forming a covering for an upper flange of a flanged beam or the like on which rests a floor or the like, including applying adherent means to the upper surface of a shooting strip, placing said strip in position adjacent the edge of the flange to be covered, pressing said strip upwardly against said floor to cause said material to adhere to the lower surface of said floor, and shooting cementitious material into place between said shooting strip and said beam to cover said flange. 55 60

5. A method of forming a cementitious covering for a flange at the upper edge of a flanged beam or the like on which a floor rests, comprising attaching a form to the lower surface of the floor by the use of quick setting plastic material and in a position adjacent the edge of said flange, shooting cementitious material into position between 70 said strip and said beam and around said flange, and removing said form. 65

6. A method of forming a cementitious covering for one of two engaging members which includes securing a shooting strip in position on one of said members by quick setting material placed therebetween, shooting cementitious material into position and removing the strip. 75 80

7. A method of forming a cementitious covering for one of two adjacent members which includes securing a form in position on the other of said members by quick setting material placed therebetween, placing cementitious material in the form, and removing the form. 85

In testimony whereof he affixes his signature.

WILLIS LERICHE.
